UNITED STATES PATENT OFFICE.

ENOK O. MILLER, OF OAKLAND, CALIFORNIA.

DESIGN FOR A TIE-PIN.

43,407.

Specification for Design.

Patented Dec. 31, 1912.

Application filed October 8, 1912. Serial No. 724,656. Term of patent 3½ years.

To all whom it may concern:

Be it known that I, ENOK O. MILLER, a citizen of the United States, residing at Oakland, in the county of Alameda and State of California, have invented a new, original, and ornamental Design for a Tie-Pin, of which the following is a specification, reference being had to the accompanying drawings, forming a part thereof.

The figure is a perspective view of a tie pin, illustrating my design.

I claim:

The ornamental design for a tie pin, as shown.

In testimony whereof I affix my signature in presence of two witnesses.

ENOK O. MILLER.

Witnesses:

W. A. STOCK,

M. M. ESCHERICH.

Copies of this patent may be obtained for five cents each, by addressing the "Commissioner of Patents, Washington, D. C."
